UNITED STATES PATENT OFFICE.

HENRY BREER, OF DE WITT, NEW YORK, ASSIGNOR TO CAROLINE H. BREER,
OF SAME PLACE.

APPARATUS FOR DRYING FERTILIZERS.

SPECIFICATION forming part of Letters Patent No. 313,401, dated March 3, 1885.

Application filed June 19, 1884. (No model.)

To all whom it may concern:

Be it known that I, HENRY BREER, of De Witt, in the county of Onondaga, in the State of New York, have invented new and useful 5 Improvements in Desiccating Apparatus, of which the following, taken in connection with the accompanying drawings, is a full, clear, and exact description.

This invention relates to the class of desiccating apparatus which are designed more particularly for the treatment of animal matter for fertilizers, and has special reference to such of said apparatus in which the substance to be treated is carried in a revolving cylinder which 15 is subjected to the requisite heat to expel the moisture from said substance.

The object of my present invention is to obtain a greater and better distributed heating-surface in and around the desiccating-cylinder and to keep the heating-surfaces clean; and to that end the invention consists of the peculiar combination and arrangement of devices connected with the desiccating-cylinder, as hereinafter fully described, and specifically 25 set forth in the claims.

In the annexed drawings, Figure I is a longitudinal section of a desiccating apparatus provided with my improvements, portions of the desiccating-cylinder being broken away 30 to better illustrate the internal arrangement of the same; and Fig. II is a vertical transverse section on line $x x$, Fig. I.

Similar letters of reference indicate corresponding parts.

A represents the furnace in which to generate the heat required for the desiccating process.

B denotes an elongated combustion-chamber, which communicates with the furnace A, 40 and has arranged longitudinally through it the revolving desiccating-cylinder C, the interior of which communicates with the combustion-chamber at the end farthest from the furnace, the opposite end of the cylinder connecting 45 with the smoke-stack D, and thus the products of combustion are made to pass longitudinally through the cylinder C.

In order to obtain a better distribution of the heat around the exterior of the cylinder,

I form around the same a spiral partition, a, 50 preferably in the form of a spiral flange secured to the cylinder, as shown in Fig. I of the drawings, said partition causing the products of combustion to pass completely around the cylinder during the rotation of the latter. 55

Longitudinally through the center of the cylinder is extended a flue, E, which communicates at one end with the stack D, and may have its opposite end either closed or open to convey a portion of the products of combustion from the farthest end of the combustion-chamber to the smoke-stack. 60

From the longitudinal flue E, through the side of the cylinder, are extended radial pipes F, arranged at proper intervals in the length 65 of the cylinder, said radial pipes serving to convey currents of the products of combustion from the combustion-chamber to the flue E, and greatly increasing the heating-surface in the cylinder. Besides this, the radial flues 70 form arms which serve to agitate and break up the substance under treatment.

In order to keep the described internal heating-surfaces of the cylinder clean, I extend longitudinally through the cylinder chains b, 75 which are suspended from the inner side of the cylinder by short chains c, so as to allow the longitudinal chains to drag on the inner surface of the cylinder during the rotation of the same, and thus scour said surface, which scouring 80 process is assisted by chains d d, suspended from the longitudinal chains b, as illustrated in Fig. I of the drawings. The surface of the radial pipes F F, I keep clean by means of chains e e, hung slack across the cylinder at the side 85 of said pipes, as shown in Fig. II of the drawings. In the rotation of the cylinder the chains e e are dragged across the pipes and lengthwise the same, and thus serve to scour the pipes, said chains also aiding the stirring and breaking up of the substance under treatment. 90

Having described my invention, what I claim as new is—

1. In combination with the combustion-chamber, a rotary desiccating-cylinder and a 95 smoke-flue extended longitudinally through said cylinder, adapted to carry the products of combustion from the furnace to the chimney.

2. In combination with the combustion-chamber and the rotary desiccating-cylinder, a smoke-flue extended longitudinally through the cylinder and radial flues extended from 5 the longitudinal flue through the side of the cylinder, substantially as set forth and shown.

3. In combination with the combustion-chamber and the desiccating-cylinder arranged in said chamber, spiral partitions between 10 the exterior of the cylinder and interior of the combustion-chamber, as and for the purpose specified.

4. The combination, with the rotary desiccating-cylinder, of scouring-chains connected 15 to the cylinder and adapted to drag on the internal surface thereof, substantially as specified.

5. The combination, with the rotary desiccating-cylinder, of chains extended longitudinally 20 through the cylinder and suspended from the interior thereof, substantially as and for the purpose specified.

6. The combination, with the rotary desiccating-cylinder, of chains extended longitudinally through the cylinder and suspended from 25 the interior thereof, and chains suspended from the longitudinally-disposed chains, substantially as described and shown, for the purpose set forth.

7. The combination, with the rotary desiccating-cylinder, of pipes extended across the interior of the cylinder and chains hung slack across the cylinder at the side of said pipes, substantially as described and shown, for the purpose specified. 30

In testimony whereof I have hereunto signed my name and affixed my seal, in the presence of two attesting witnesses, at Syracuse, in the county of Onondaga, in the State of New York, this 26th day of May, 1884.

HENRY BREER. [L. S.]
